CONVERTIBLE CHAIR, IRONING BOARD,
AND STEPLADDER

Charles R. Scarborough, Knoxville, Tenn.

Application February 1, 1946, Serial No. 644,851

1 Claim. (Cl. 155—41)

1

My invention relates to furniture and more particularly to a three-in-one piece of furniture.

The object of my invention is to provide a piece of furniture which by simple manipulations can be arranged to be used for three different purposes.

A further object of my invention is to provide a piece of furniture having interconnected but relatively movable parts adapting the piece of furniture to be used selectively as a high chair, a step ladder or an ironing board.

Other objects of my invention may appear in the following specification describing my invention with reference to the accompanying drawing illustrating a preferred embodiment thereof. It is however to be understood that my invention is not to be limited or restricted to the exact construction and combination of parts described in the specification and shown in the drawing, but that such changes and modifications can be made, which fall within the scope of the claim appended hereto.

In the drawings:

Figure 1 is a side view of the three-in-one piece of furniture forming the subject matter of my invention arranged to be used as an ironing board.

Figure 2 is a top plan view of Figure 1.

Figure 3 is a sectional view taken on line 3—3 in Figure 1 shown in a larger scale.

Figure 4 is a front view of my three-in-one piece of furniture arranged to be used as a high chair.

Figure 5 is a top view of Figure 4.

Figure 6 is a side view of the three-in-one piece of furniture arranged for use as a step ladder.

Figure 7 is a bottom plan view of a unit consisting of the body of the ironing board and the arms of the high chair adapted to be formed by my three-in-one piece of furniture, and

Figure 8 is a perspective view of a locking unit used to secure the body of the ironing board in horizontal position.

Referring now to the drawings in detail the three-in-one piece of furniture forming the subject matter of my invention has a pair of front legs 10 and a pair of rear legs 11. One front leg and one rear leg is attached to each of two side boards 12, so that they slant forwardly and rearwardly in relation to each other. Approximately in the center of the side boards 12 a top board 13 extends across the side boards and these boards are firmly and securely fastened to the top board in any desired conventional manner.

The side boards 12 are formed so that the legs 10 and 11 slant outwardly as shown in Figures 2, 4 and 5.

Between the two front legs a plurality of horizontally extending boards are arranged in regular intervals to each other and securely fastened to the front legs, thereby forming steps 14.

A support board 15 is hingedly fastened to the rear edge of the top board 13 as clearly shown at

10 16. On the rear edge of the support board 15 an ironing board 17 is securely fastened in any preferred manner. The ironing board shaped in the conventional form having a tapering portion and a substantially rectangular portion. The ironing board is fastened to the support board 15 approximately at the point where the two portions join and so, that the tapering portion will point downwardly, when the support board 15 is pivoted

15 to extend horizontally as shown in Figure 6. The rectangular portion will then extend upwardly from the horizontally located board 15 forming a back 18 of a high chair formed by the legs 10 and 11, and a seat composed of the top board 13,

10 16 and a step board 19 hingedly attached to the front edge of the top board 13 as shown at 20. A pair of side arms 21 are fastened on the rectangular portion of the ironing board 17, one on each side edge thereof so that the arms extend forwardly when the ironing board is in the position shown in Figures 4 and

20 25 30 35 40 45 6 and downwardly when the ironing board is arranged in ironing position.

To convert the high chair described above into a step ladder, the step board 19 is pivoted so as to rest on the top board 13 as shown in Figure 6.

This prevents marring of the top surface of the step board, which is being used as a part of the seat of the high chair. In addition, the side arms 21 can be used as guides and hand rails when the

side boards 12 adjacent their rearward ends. The center portion of the stirrup brace is slidably arranged in the guideway 23.

A latch member 25 has a substantially U-shaped cross-section. It has a bottom element 26 from which two side elements 27 extend upwardly at right angles. Coaxial holes 28 are provided in the upper rear corner of said elements and a pin 29 extending through the stiffening rib 22 and the holes 28 attaches the latch member pivotally to the rib, said rib being arranged between the side elements. The rear corners of the side elements extend upwardly to the lower edge of the guideway 23 while the forward corners abut the underside of the ironing board. To urge the latch member into the described position a spiral spring 30 is located between the rib 22 and the rearward end of the bottom element 26, which extends rearwardly beyond the side elements 27 and is bent downwardly to form a finger piece 31 to operate the latch member 25.

This member and the stirrup brace are so arranged that when the ironing board is pivoted into horizontal position the center portion of the brace 24 will slide into the fore end of the guideway 23 and the front edges of the side elements of the latch member 25 will prevent it from sliding out of this place, so that the stirrup brace will hold the ironing board 17 securely in horizontal position.

By pressing the finger piece 31 upwardly the rear corners of the side elements release the stirrup brace so that the ironing board can be pivoted downwardly into the position shown in Figures 4 and 6.

Having described my invention what I claim and desire to secure by Letters Patent is:

A convertible furniture item adapted to provide an ironing board, a high chair or a step-ladder, said item comprising a pair of side boards, a top

board secured at its ends to the top edges of said side boards securing said side boards in predetermined, spaced-apart relationship, four mutually diverging legs secured at their upper ends, 5 two to each of said side boards, ladder steps secured between one pair of legs, a support board hinged along one edge to said top board, an ironing board secured intermediate its length to the opposite edge of said support board, a stiffening 10 rib secured to the under side of said ironing board at one side of said support board and having a cut-away portion providing a guideway adjacent said ironing board, a stirrup brace pivotally secured at its ends to said side boards and 15 having its intermediate portion slideable in said guideway, and a latch member pivotally secured to said stiffening rib and spring urged in a direction to constrain the intermediate portion of said brace to one end of said guideway to support said 20 ironing board in generally horizontal position and being manually movable to release the intermediate portion of said brace to permit tilting said ironing board to a generally vertical position wherein the upper part thereof constitutes a 25 chair back, the seat of which comprises said support board and top board.

CHARLES R. SCARBOROUGH.
